DEVICE FOR HOLDING BOARDS
WHILE BEING NAILED

Albert Hidalgo, Sr., Opelousas, La.

Application March 29, 1955, Serial No. 497,493

1 Claim. (Cl. 254—17)

This invention relates to a device in the form of a jack, designed primarily for use by carpenters, and aims to provide a device or tool which will facilitate the center match fitting of boards, in the construction of walls, floors or the like.

The primary object of the invention is to provide a device of this character, which may be operated to move the boards to their proper fitted positions for nailing to the studding of the building.

An important object of the invention is to provide a device of this character that may be operated to hold the boards in place during the nailing operation of the boards.

Still another object of the invention is to provide a device of this character which may be readily adjusted for positioning over studding of a building and to which boards are being nailed and temporarily held in position by the device.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing:

Figure 1 is a fragmental perspective view of a building illustrating a jack device, constructed in accordance with the invention as positioned for holding a board in position for nailing.

Fig. 2 is a plan view of the device fitted over studding.

Fig. 3 is a fragmental enlarged elevational view illustrating the operating lever and means for holding the operating lever against movement.

Fig. 4 is a transverse sectional view through the studding illustrating the device in elevation.

Referring to the drawing in detail, the device comprises a pair of bars 5 having curved ends 6 adapted to straddle a studding of a building to hold the device in position for operation.

Aligning openings 7 are arranged in pairs and are formed in the curved ends 6 for the reception of the threaded shank 8 which is provided with a crank 9 at one end thereof for rotating the shank 8. It will thus be seen that by rotating the shank 8 the curved ends 6 of the bars 5 may be moved towards each other to grip the studding over which the device is positioned. By rotating the shank 8 in the opposite direction, the curved ends 6 of the bars 5 may be moved away from the studding to release the device.

The bars 5 are held together by means of the U-shaped connecting bar 10 which is shown as having its ends riveted to the bars 5 at such a point throughout the length of the device that the curved ends of the bars 5 may flex towards and away from each other.

2

The reference character 11 indicates a lever which has its lower end curved laterally providing a jaw 12. Cooperating with the jaw 12 is a jaw 13 formed at the lower end of the substantially short bar 14 which is secured to the lever 11 and held in spaced relation therewith by means of spacers 15 which are disposed between the bars 11 and 14 and are mounted on bolts 16.

The reference character 17 indicates a pivoted arm formed with a bifurcated end 18 that connects with the bars 5 at points substantially intermediate the ends thereof. This pivoted arm 17 is of a length to extend between the bars 11 and 14, as better shown by Fig. 1 of the drawing, the arm 17 having teeth 19 between which the spacers 15 rest as the lever 11 is swung forwardly or rearwardly in operating to position and hold a board to be nailed.

It might be further stated that the ends of the jaws 12 and 13 extend beyond the lower edges of the bars 5 and below the pivot points 20 thereof, with the result that the lever 11 is moved to the right from the position shown in Fig. 3 of the drawing, and the extended ends 21 of the jaws 12 and 13, will contact with the board being positioned with the device to move the board into close contact with the adjacent board.

In operation the device is positioned on studding such as indicated at A in the drawing, and the curved ends 6 of the bars 5 are clamped to the studding in the proper position to leave sufficient space at the end of the device for supporting the lever 11, to permit the board to be positioned and held by the device, to be laid adjacent to a board which has been already secured.

The lever 11 is now moved to the right causing the board to be moved in the desired direction or into close contact with the adjacent board already positioned. The pivoted arm 17 is now moved to a position so that the teeth 19 fall opposite to the bolt 16, whereupon the lever 11 is held in its stationary position, behind the person using the boards to nail the boards in their proper positions.

The tool may now be moved along the beam and the operation repeated until the entire surface has been covered.

Having thus described the invention, what is claimed is:

A device for holding boards for nailing, comprising a pair of bars arranged in parallel relation and having downwardly curved ends disposed opposite to each other, said curved ends having threaded openings, a threaded shank movable within said openings for moving said curved ends into gripping relation on a beam, securing the device to a beam, a lever pivotally mounted at the other ends of said bars, said lever including jaws extended below said bars for contact with a board to be nailed, a pivoted arm secured to said bars at intermediate transversely aligned points thereon, said arm being formed with spaced keeper notches, and a locking pin carried by said lever engageable in a selected keeper notch for holding said lever in position against accidental movement in gripping a board to be nailed, said lever including two spaced apart components, outwardly flared at their lower ends to form a fork, the arms of said fork being pivotally secured, one to each bar in transverse alignment, said locking pin extending transversely between said components.
